Primary Examiner — Carol P Rademaker(74) *Attorney, Agent, or Firm* — Marshall, Gerstein & Borun LLP; Richard M. LaBarge**CLAIM**

The ornamental design for a bottle, as shown and described.

DESCRIPTION

FIG. 1 is top, front perspective view of a bottle of the design.

FIG. 2 is a bottom, rear perspective view of the bottle.

FIG. 3 is left-side elevational view of the bottle.

FIG. 4 is a rear elevational view of the bottle.

FIG. 5 is a right-side elevational view of the bottle.

FIG. 6 is a front elevational view of the bottle.

FIG. 7 is a top plan view of the bottle; and,

FIG. 8 is a bottom plan view of the bottle.

The broken lines of details shown on the bottom of the bottle and threads shown on the pour spout are included for the purpose of illustrating environmental structure and form no part of the claimed design.
